(57) **CLAIM**

The ornamental design for a vehicle lamp, as shown and described.

DESCRIPTION

FIG. 1 is a top, front, and right side perspective view of the vehicle lamp;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view taken along the line VIII-VIII in FIG. 2; and,

FIG. 9 is a cross-sectional view taken along the line IX-IX in FIG. 2.

The dot-dash broken lines in FIGS. 8 and 9 define the bounds of the claimed design and form no part thereof. The evenly-dashed broken lines depict portions of the vehicle lamp that form no part of the claimed design.

1 Claim, 9 Drawing Sheets
